LUCIEN H. KELLOGG, OF MONROE, OHIO.

Letters Patent No. 84,360, dated November 24, 1868.

IMPROVEMENT IN HORSE-SHOES.

The Schedule referred to in these Letters Patent and making part of the same.

To all to whom it may concern:

Be it known that I, LUCIEN H. KELLOGG, of Monroe, in the county of Ashtabula, and State of Ohio, have invented certain new and useful Improvements in Horse-Shoes; and I do hereby declare that the following is a full and complete description of the same, reference being had to the accompanying drawings, making a part of this specification, in which—

Figure 1 is a view of the outside of the shoe.

Figure 2 is a side view.

Figure 3, a detached section.

Like letters of reference refer to like parts in the views.

A, fig. 1, is the shoe, which is made of common cast or malleable iron, around the outer edge of which is raised a deep flange, B, adding thereby largely to the strength of the shoe.

The toe-calk C, fig. 3, is made of steel, and separate from the shoe, but is attached or fixed to the same, by being dovetailed to it, or made to slide in between the checks D, which, it will be seen, are arranged tapering towards the front. Thus the calk is made to wedge in as it slides into place, and is prevented from falling out by the under bevel of the sides of the calk, and the screw or nail B'.

The heel-calks E are also made of steel, and are fixed to the heel by dovetailing, as shown in fig. 2.

The flange B extends entirely around the shoe upon the under side, and forms a rest for the front end of the toe-calk C, so that the latter cannot be forced out of the dovetailed guides D.

It will be observed that the heel-calks do not stand across the heel, as do the calks of an ordinary shoe,

but that they are lengthwise with the curve of the side. This position of the calk is much easier for the horse, as it supports the heel further forward; it also allows of the shoe being made wider at the heel, and still retain the same size calk, and thus will prevent an over-reaching horse from interfering.

By thus dovetailing the calks to the shoe, they can be readily replaced, without the necessity of welding and refitting the shoe to the foot, as must be done with the ordinary wrought-iron ones.

This shoe is found to be durable, and not more liable to break than wrought ones. The flange, as above said, gives to them the strength of the best forged.

They are very much cheaper and more convenient than the common shoe, as any person of ordinary skill can put them on the foot himself, as they are screwed on, instead of being nailed in the ordinary way, which, however, may be nailed on if so desired.

I am aware that horse-shoes have been made, in which the calks are dovetailed, but as this does not constitute my invention, I do not therefore claim it; but

What I claim as my improvement, and desire to secure by Letters Patent, is—

The described construction of the horse-shoe, having the flange B extending entirely around its under side, forming a rest for the front end of the toe-calk C, and adapted to receive the dovetailed heel-calks in such a manner that they shall rest upon the flange, longitudinally of the same, as herein shown and described.

LUCIEN H. KELLOGG.
